Fiorentino Muccarone

Harold E. Stoebleton,
his ATTORNEY

UNITED STATES PATENT OFFICE

FIORENTINO MACCARONE, OF ROCHESTER, NEW YORK.

HEEL ATTACHMENT FOR SHOES.

Application filed January 4, 1923. Serial No. 610,636.

To all whom it may concern:

Be it known that I, FIORENTINO MACCARONE, a citizen of the United States of America, residing at Rochester, in the county 5 of Monroe and State of New York, have invented certain new and useful Improvements in Heel Attachments for Shoes, of which the following is a specification.

My invention relates to a heel attachment 10 for shoes, and has for its purpose to provide a heel bracing device for ladies' shoes, with a view to preventing the heel breaking away from the sole.

Various devices for this purpose have been 15 proposed and manufactured, and it is a particular object of this invention to afford a structure that can be manufactured and applied at a minimum cost, in addition to carrying out its purpose in a most efficient way.

20 A further purpose of my invention is to provide means that will effectually prevent a heel breaking away from the sole, and in such manner as not to weaken the shoe in any other respects or lessen its wearing qualities.

25 Another purpose of the improvement is to provide a structure that can be readily incorporated in a shoe and which is thoroughly practical in every respect.

To these ends, the invention comprises the 30 structure that will be clearly understood from the following description in conjunction with the accompanying drawing, the novel characteristics of the invention being pointed out in the claim following the description.

In the drawing:

Figure 1 is sectional view, partially in elevation, of a shoe showing the application of the invention in its preferred embodiment;

40 Figure 2 is a plan view;

Figure 3 is a perspective view of the heel bracing member, and

Figure 4 is a sectional view on the line 4-4 of Figure 1.

45 The invention may be carried out in a variety of ways, and in its preferred aspect includes a heel 1 and a sole 2 of usual formation, and arranged against the inner surface of the sole is a metallic arch stiffening plate 3 carried by the inner sole 4.

The heel bracing member is preferably made of metal of the general form appearing in Figures 1 and 3, and comprises a rear end 5 having inwardly bent integral prongs for

engagement with the heel and an opening 55 to receive a nail for attaching the plate to the heel. The bracing member is preferably narrow and somewhat elongated, and its forward end 8 extends from the outer surface of the sole forwardly and toward the inner surface of the sole through a narrow opening 60 provided in the sole for the purpose. The opening in the sole is fashioned somewhat like a slot, and loosely receives the forward end of the bracing member which is permitted to contact with the metal stiffening plate 5 and have slight play against said plate when the shoe is in action. This gives a certain amount of resiliency and flexibility 65 to the shoe, while at the same time the heel 70 is held with sufficient firmness to prevent its accidental displacement relatively to the sole.

In assembling the parts, the sole, with the upper and heel attached, is slotted in any convenient way to receive the forward end of 75 the bracing member, which is inserted into said slot or opening in the sole, as indicated in Figure 1. The rear end of the bracing member is then attached to the breast 80 of the heel, and in order to afford a smooth exterior surface on the breast of the heel, the latter is preferably grooved or undercut to receive the body portion of the bracing member. The bracing member and heel are covered by the lower split portion 85 90 of the sole, as usual in this general type of shoe.

By slotting the sole, and arranging the forward end of the bracing member loosely therein, as shown, I provide a very economical and practical method of securing the forward end of the bracing member, and such that the heel is securely held against accidental displacement. No rivets or nails are required at the forward end of the bracing member and there is no likelihood of the bracing member becoming disengaged from the sole. At the same time there is afforded sufficient play or lost motion between the bracing member and the sole to impart a nice 95 100 flexibility to the entire construction.

The details of the invention may be modified without departing from the fundamental novel characteristics, and it is intended to cover by this application any changes coming within the underlying spirit of the improvement or scope of the following claim.

I claim:

In a shoe, the combination with a heel and sole, of an arch stiffening plate located adjacent the inner surface of the sole, said sole having a narrow opening extending from its outer surface forwardly to its inner surface to a point immediately under said stiffening plate, and a heel bracing member having its rear end curved downwardly and attached to the breast of the heel and its forward end extending into said opening of the sole and contacting loosely with said stiffening plate.

In witness whereof, I have hereunto signed my name.

FIORENTINO MACCARONE.
